UNITED STATES PATENT OFFICE.

AUGUST J. KREUZKAMP, OF BROOKLYN, NEW YORK, ASSIGNOR TO THE ENGLANDER SPRING BED COMPANY, OF BROOKLYN, NEW YORK, A CORPORATION OF NEW YORK.

WIRE MATTRESS.

1,100,701.

Specification of Letters Patent. Patented June 16, 1914.

Application filed April 7, 1911. Serial No. 619,500.

To all whom it may concern:

Be it known that I, AUGUST J. KREUZKAMP, a citizen of the United States, residing at Brooklyn, in the county of Kings and State 5 of New York, have invented certain new and useful Improvements in Wire Mattresses, of which the following is a specification.

This invention relates to wire mattresses, 10 the object of the invention being to provide an improved wire or spring mattress so constructed that the spreading of the stuffed mattresses will be prevented either sidewise or endwise so that the same will be maintained in its box-like form at all times.

In the drawings accompanying and forming part of this specification, Figure 1 is a perspective view showing one form of structure with which this improvement may be 20 used, to-wit, a divan with one of the sections forming a back and therefore in the form of a sofa bed; Fig. 2 is a perspective view illustrating the structure in the form of a double bed; Fig. 3 is a perspective view illustrating 25 the structure folded in readiness for shipping or storing; and Fig. 4 is an enlarged detail view of one corner of the structure.

Similar characters of reference indicate 30 corresponding parts throughout the drawings.

The divan with which this improved wire mattress is used comprises a pair of sections 2 and 3 hinged together so that one section, as 3, may be level with the other to form a 35 double bed or raised to form a back or folded over upon the section 2 to permit the same to be readily stored or shipped. Each of these sections comprises, in the preferred embodiment thereof shown, a pair of cross 40 angle bars 4, each consisting of a horizontal member 5 for the reception of the usual helical springs 6 to which the usual spring mattress or metallic fabric 7 is attached, and an upright member 8. These cross angle 45 members are supported by suitable brackets 9 spaced and maintained apart by suitable side bars 10, which latter carry folding legs 11. In the form shown each of the legs, which may be made of tubing and provided 50 with a suitable foot or caster, is provided at its upper end with a casting 12 to which the leg is rigidly secured. This casting, in the form shown, comprises a sleeve 13 into which the upper end of the leg may be inserted and riveted, and a horizontally or

transversely located sleeve 14 encircling and loosely mounted on the side bar. The transversely located sleeve is provided with a pair of spaced projections or brackets 15 and 16, each provided with a slot 17 for the 60 reception of a headed bolt 18. Each of these brackets in the present instance is shown as a single member adapted to engage or overlap at the side a correspondingly formed projection or bracket 19 carried by a sleeve 65 20 bolted to the side bar. This last bracket or projection is preferably provided with a bolt opening 21, while the brackets 15 and 16 are provided with open-ended slots thereby to permit the leg to be shifted into overlapping engagement with the bracket 19 carrying the bolt. Thus, by this construction the leg may be located at any desired point along the side bar, while the bracket 19 may also be swung laterally so as to bring it into 75 proper position to permit the leg bracket to be clamped thereto with the leg in a proper perpendicular position.

When it is desired to clamp each leg in its vertical supporting position, the leg is 80 shifted toward the bracket 19 so that one of the leg brackets, as 15, will project past the bracket 19, overlapping the same at the side thereof, whereupon, by turning up the wing nut 22 on the bolt, the leg will be readily 85 clamped in such position. When it is desired to fold the leg under the mattress the wing nut is released, the leg shifted inward or away from the bracket 19 and swung upward and then shifted back to bring its 90 other projection 16 at the side of the projection 19, and the wing nut then retightened, whereupon the leg will be held in its folded position. Thus, in the present structure all of the legs can be folded under the metallic 95 mattress in a manner which will be readily understood, so that the structure can be readily shipped or stored away in a small space.

The section 3 of the divan is hinged in 100 any suitable manner to the rear side of the seat section 2 and is provided with foldable legs supported in a similar manner to those just described, so that these legs can likewise be folded in a similar manner to that 105 hereinbefore set forth. Some suitable means may be provided for holding the section 3 in an upright position when it is intended to use the structure with a back. On lowering the back section and unfolding 110

the legs a double bed is formed. On raising it to a perpendicular position and folding the legs a divan, with a back is formed. On throwing forward the back and resting it horizontally over the seat section and folding the legs the structure is in a compact form ready to be shipped or stored away in a comparatively small space.

Carried along the outer edge of the seat section and the outer edge of the back section is a suitable side guard 25 for preventing the spreading of the mattress, thereby to maintain it in its box-like form. This side guard may be formed in any desired manner, but in the present instance it is formed of a metallic fabric connected by helical springs with the upright member 8 of the cross angle bar, so that, it will be observed that the stuffed mattress is inclosed not only at its sides but also at its ends, at its sides by means of the metallic fabric side guards and at its ends by the cross angle bars, so that the stuffed mattress will not protrude or fall over either the sides or the ends of the structure and will at all times be maintained in its box-like form.

The side guards are usually of slightly less height than the height of the stuffed mattress, so that when the structure is shipped with the stuffed mattresses in position the side guards will be held somewhat spaced apart, but when shipped or stored without such stuffed mattress one side guard will overlap somewhat the other. The guards are preferably attached at intervals to the bottom in any suitable manner.

From the foregoing it will be observed that when the divan is in the form of a sofa bed, with its back in an upright position, the upper edge of the stuffed mattress is confined by the side guard located at this point, while the opposite edge of the mat-

tress is confined by the side guard located along the outer edge of the seat section, and that the same is true when the structure is 45 in the form of a double bed, or when the sections are folded one on top of the other.

In the present embodiment it will be observed that the two sections are substantially duplicates one of the other so that 50 either one of them may be raised to form the back.

From the foregoing it will be observed that the upwardly extending portions 8 of the end angle bars, together with the side 55 guards extending upwardly above the fabric bottom or mattress body 7, form a pocket for the soft or stuffed mattress when the structure is in the form of a bed structure as in Fig. 2, or when in the form of a divan 60 as in Fig. 1, since each section 2 and 3 has the upwardly extending end portions 8 and side guard, so that in either form of the device the soft or stuffed mattress is prevented from shifting or spreading laterally in any 65 direction and this is also the case when the structure is made as an ordinary one-piece wire mattress.

I claim as my invention:

A wire mattress embodying a supporting 70 frame and a mattress body attached at its ends to the sides of the end bars of said frame and extended upwardly at its side edges to form in conjunction with said end bars a pocket to receive a stuffed mattress 75 therein and to retain the same against shifting or spreading laterally in any direction.

Signed at 1821 Park Row Building, New York, N. Y., this 4th day of April, 1911.

AUGUST J. KREUZKAMP.
